SELF POWERED AUTOMATIC WATER
TREATING PLANT

Olin A. Sims, Beeville, Tex.

Application June 1, 1936, Serial No. 82,945

3 Claims. (Cl. 210—22)

This invention relates to water treating plants and has for the primary object the provision of a self-powered automatic device of the above stated character which will introduce treating liquid into a water main proportionately to the water taken from the main and which will thoroughly mix the treating liquid with the water.

5

With these and other objects in view, this invention consists in certain novel features of construction, combination and arrangement of parts to be hereinafter more fully described and claimed.

10 For a complete understanding of my invention, reference is to be had to the following description and accompanying drawings, in which

15 Figure 1 is a side elevation, partly in section, illustrating a self-powered automatic water treating plant constructed in accordance with my invention.

20 Figure 2 is a side elevation partly in section showing the opposite side of the device from that shown in Figure 1.

Figure 3 is a plan view partly in section showing the device.

25 Figure 4 is a sectional view taken on the line 4—4 of Figure 1.

Figure 5 is a sectional view taken on the line 5—5 of Figure 3.

30 Figure 6 is a fragmentary elevational view showing the arrangement of the pumps and the connection therebetween.

35 Referring in detail to the drawings, the numeral 1 indicates a support on which is mounted a casing 2. Operating within the casing 2 is a water wheel 3 of conventional construction and is secured to a shaft 4 extending through one of the sides of the casing and is rotatably supported thereby.

40 Pipes 5 and 6 extend through one of the end walls of the casing and are connected to each other exteriorly of the casing and to a water main 7 by a coupling 8. The pipes 5 and 6 are arranged in superimposed relation and the pipe 5 has connected thereto a nozzle 9 provided with 45 a comparatively small discharge orifice. The nozzle 9 directs water into the pockets or against the fins of the water wheel. A relief valve 10 is secured to the pipe 6 and is of a conventional construction and located within the casing, the outlet of which is indicated by the character 11. The outlet 11 has a nozzle 12 connected thereto. The orifice of the nozzle 12 is considerably larger than the orifice of the nozzle 9. The nozzle 12 directs water against the fins or pockets 50 of the water wheel when the relief valve 10

opens. An outlet main 14 is connected to the casing having a conventional type of control valve (not shown) whereby the water in the main 7 may be disposed as desired.

5 A bracket 15 is located adjacent one side of the casing 2 and forms a guide 16 for a cross head 17 and also provides a support for a pump cylinder 17'. The bracket 15 is secured to a gear housing 18 mounted on the base of the device. Operating within the gear housing 18 are reduction gears 19, one of the shafts thereof being indicated by the character 20 and is connected to the shaft 4 by a coupling 21. Another one of the shafts of the reduction gearing is indicated by the character 22 and has secured thereto a fly wheel 23. A pitman 24 is eccentrically pivoted to the fly wheel and is pivoted to the cross head 17. A pump plunger 24' is secured to the cross head and extends into the pump cylinder 17', completing a positive force pump indicated generally by the character A. A stuffing gland 25 is provided between the pump cylinder 17' and the plunger 24'. The pump cylinder is provided with inlet and outlet pipes 26 and 27 to which are connected check 25 valve 28. The check valve 28 of the outlet pipe has connected thereto a pipe 28' which is in turn connected to the water supply pipe 7 adjacent to the coupling 8. The check valve 28 of the inlet pipe has connected thereto a pipe 29 which 30 is connected to an outlet of a pump B. The pipe 29 has located therein a sight gauge 29'. The pump B includes a cylinder 30 supported by the bracket 15 and paralleling the cylinder of the pump A and operating in the cylinder 35 30 is a plunger 31 terminating in a screw threaded stem 32. The screw threaded stem 32 is operated by a bracket 33 secured to the cross head 17 so that the pumps A and B operate in unison. The inlet of the pump B has connected 40 thereto a flexible hose 34 adapted to be inserted in water treating liquid of a container 35. This container is of a type employed for shipping the water treating liquid from the manufacturer. The inlets and outlets of the pump B have check 45 valves therein. The pump B acts as a measuring medium and furnishes to the pump A a measured amount of liquid during each reciprocation of its plunger 31. The stroke of the plunger 31 may be varied by adjusting the stem thereof in 50 the bracket 33 thereby permitting the measured amounts dispensed by the pump B to be varied. The sight gauge permits the operator to readily determine the flow of treating liquid from the measuring pump to the pump A. The pump A 55

forces the measured treating liquid into the water main against the pressure of water therein.

The relief valve 10 is of the self-seating type and also the back pressure of the water within 5 the casing aids in seating this valve having communication therewith by way of the nozzle 12.

In operation, when the control valve of the outlet main 14 is closed the pressure of water within the casing is equal to the pressure of the water within the main 7, this being accomplished 10 by the nozzle 9 feeding water from the main 7 into the casing. As soon as the control valve is cracked or slightly opened to permit water to escape from the casing 2 the casing is fed with 15 water from the main 7 by way of the nozzle 9. The water impinging against the water wheel rotates the latter. The rotation of the water wheel operates the pump which draws the treating liquid from the container 35 and introduces 20 the same into the main 7. As the control valve of the outlet main is further opened the pressure decreases in the casing 2 and the pressure in the water main overcomes the action of the relief valve 10 and permits water to be fed into the 25 casing both by the nozzle 12 and the nozzle 9 rotating the water wheel at a faster rate of speed, consequently operating the pumps faster so as to increase the amount of treating liquid introduced 30 into the water in the water main 7. Thus it will be seen that the treating liquid is introduced into the water of the water main 7 proportionately to the amount of water taken or allowed to escape from the outlet main. The rotation of the water wheel within the casing agitates the water and 35 treating liquid so that they thoroughly commingle before passing from the casing by way of the outlet main.

A water treating plant of the character described will operate and treat the water regardless of whether a large or small stream is being 40 passed through it, and also where it is necessary to treat the water with as many as three different chemicals, as many as three different pumps can be geared to one water motor. The 45 one water motor having the power to drive the three pumps without inserting a booster pump in the line to build up the water pressure. The pump has a single acting piston which does not require packing, therefore, no internal packing trouble.

50 It is to be understood, of course, that while I have herein shown and described but one specific embodiment of the invention changes in form, construction and method of application and operation may be made within the scope of the appended claims.

Having described the invention, I claim:

1. A water treating plant comprising a casing, 55 a water wheel mounted in said casing, a con-

trolled water outlet for said casing, nozzles located in the casing for directing water under pressure against said water wheel, water inlet pipes extending into the casing and one of said inlet pipes connected to one of the nozzles, a self-closing relief valve connecting the other water inlet pipe to the other nozzle and opened by the water pressure in the inlet pipe connected thereto when the water pressure in the casing falls below the pressure of the water in the last-named inlet pipe, a water supply pipe connected to said inlet pipes, and means driven by said water wheel for injecting treating fluid into the water supply pipe.

2. A water treating plant comprising a casing, 15 a water wheel mounted in said casing, a controlled water outlet for said casing, nozzles located in the casing for directing water under pressure against said water wheel, water inlet pipes extending into the casing and one of said inlet pipes connected to one of the nozzles, a self-closing relief valve connecting the other water inlet pipe to the other nozzle and opened by the water pressure in the inlet pipe connected thereto when the water pressure in the casing falls below the pressure of the water in the last-named inlet pipe, a water supply pipe connected to said inlet pipes, and means driven by said water wheel for injecting treating fluid into the water supply pipe.

3. A water treating plant comprising a casing, 35 a water wheel mounted in said casing, a controlled water outlet for said casing, nozzles located in the casing for directing water under pressure against said water wheel, water inlet pipes extending into the casing and one of said inlet pipes connected to one of the nozzles, a self-closing relief valve connecting the other water inlet pipe to the other nozzle and opened by the water pressure in the inlet pipe connected thereto when the water pressure in the casing falls below the pressure of the water in the last-named inlet pipe, a water supply pipe connected to said inlet pipes, a pair of pump cylinders and one of said cylinders connected to the water supply pipe and the other cylinder connected to a treating fluid supply, means connecting the cylinders, plungers operating in said cylinders, and a drive means for actuating the plungers and driven by the water wheel.

OLIN A. SIMS.
